UNITED STATES PATENT OFFICE.

JOHN S. JOHNSTON, OF ANNISTON, ALABAMA, ASSIGNOR OF SEVEN-TWELFTHS TO ROBERT G. GREEN AND FRANK P. MURPHEY, OF CHICAGO, ILLINOIS.

CHANGE-DELIVERING DEVICE.

SPECIFICATION forming part of Letters Patent No. 608,778, dated August 9, 1898.

Application filed December 30, 1897. Serial No. 664,540. (No model.)

To all whom it may concern:

Be it known that I, JOHN S. JOHNSTON, of Anniston, in the county of Calhoun and State of Alabama, have invented certain new and useful Improvements in Change-Delivering Devices; and I do hereby declare the following to be a full, clear, and exact description of the invention, such as will enable others skilled in the art to which it appertains to make and use the same.

My invention relates to an improvement in change-delivering devices, the object of the invention being to provide a device for delivering change to a customer, so as to avoid placing the change on the counter, which shall be simple in construction, ornamental in appearance, which can be utilized for advertising purposes, and which shall be effectual in all respects in the performance of its functions.

With this object in view the invention consists in certain novel features of construction and combinations and arrangements of parts, as hereinafter set forth, and pointed out in the claims.

In the accompanying drawings, Figure 1 is a view illustrating my invention, showing the device in use; and Fig. 2 is a sectional view.

A represents a hollow base or pedestal, which may be made of cast-iron or of other material, and is preferably ornamental in appearance, being made with suitable decorative depressions and protuberances. The top of the base or pedestal is preferably flat, as at 1, so as to form a broad support for a tray B. The tray B is preferably made oval in shape and provided around its edge (except at the outlet 2) with a flange 3 to prevent the accidental escape of coins placed therein by the storekeeper. A transparent plate 5, which may be of glass, celluloid, or other transparent material, is placed in the tray, and between this plate and the bottom of the tray advertising matter is placed. The advertising matter may be printed on a slip of paper or cardboard, which can be easily placed in position in the tray and readily removed therefrom by the storekeeper when it is desired to change the advertisement. The tray

will be hinged near its outlet end to one edge 50 of the base, so that its own weight will keep it normally on the base and return it thereto after it shall have been tipped by a customer.

In order to provide ready means to facilitate the tipping of the tray by the customer 55 to obtain his change therefrom, said tray is provided at its outlet end with a curved lip 6, which depends from said outlet end of the tray and is adapted to receive the fingers of the hand, as shown in Fig. 1.

My improvements are simple in construction, comprise but few parts, are ornamental in appearance, and are effectual in all respects in the performance of their functions.

Slight changes might be made in the details 65 of construction of my invention without departing from the spirit thereof or limiting its scope, and hence I do not wish to limit myself to the precise details herein set forth.

Having fully described my invention, what 70 I claim as new, and desire to secure by Letters Patent, is—

1. A change-delivering device comprising a hollow base having an extended bearing-face at its top and constituting the sole support for a tray, and a tray hinged to said base and normally bearing on said extended bearing-face and closing the hollow base, one end of said tray projecting beyond its hinged connection with the base, substantially as set 80 forth.

2. As a new article of manufacture, a change-delivering device comprising a base, a tray hinged to one edge of said base and adapted to be supported on said base and returned thereto by gravity, said tray having a portion projecting beyond said hinged connection, a plate of transparent material in said tray and advertising material between said transparent plate and the bottom of the 90 tray, substantially as set forth.

In testimony whereof I have signed this specification in the presence of two subscribing witnesses.

JOHN S. JOHNSTON.
